UNITED STATES PATENT OFFICE.

JOSIAH K. PROCTOR, OF PHILADELPHIA, PENNSYLVANIA, ASSIGNOR TO THE PHILADELPHIA TEXTILE MACHINERY COMPANY, OF PENNSYLVANIA.

DRYING-MACHINE.

SPECIFICATION forming part of Letters Patent No. 473,263, dated April 19, 1892.

Application filed August 13, 1890. Serial No. 361,934. (No model.)

To all whom it may concern:

Be it known that I, JOSIAH K. PROCTOR, of the city and county of Philadelphia, and State of Pennsylvania, have invented an Improvement in Drying-Machines, of which the following is a specification.

My invention has reference to drying-machines; and it consists of certain improvements, which are fully set forth in the following specification and shown in the accompanying drawings, which form a part thereof.

My invention relates particularly to that class of drying-machines in which the material to be dried is moved through the drying-inclosure and is subjected while moving to heat furnished by radiating-surfaces, the heated air being diffused and mixed by means of air-currents.

My invention, while designed, primarily, for the drying of wool, cotton, and other textile fiber, is not confined to the drying of any particular kind of material, but relates with equal force to any materials or goods which may be carried continuously through the drying-room, entering it at one point and issuing from it at another.

It is the object of this invention to cause the material while passing through the drying-inclosure to be subjected to successively-varying conditions as to the temperature and the humidity of the air-currents.

It is also an object of this invention to provide means for agitating or opening up the material while in transit to expose it to greater contact with the heated air.

In the drawings, Figure 1 is a longitudinal vertical sectional view on the line $y-y$ of Fig. 2 of a drying-machine embodying my invention, and Fig. 2 is a transverse vertical sectional view of the same on line $z-z$ of Fig. 1.

The directions of the air-currents are indicated in the drawings by the arrows.

A A are exterior walls or partitions forming sides, ends, top, and bottom of a drying-inclosure closed from all communication with the atmosphere except through certain openings hereinafter described. This inclosure is divided into a series of compartments B C D by means of interior vertical partitions h. The adjacent compartments B, C, and D com-

municate with each other through the openings b.

E is an endless apron or carrier extending through the inclosure A and passing over drums F F, properly supported at either end of the machine. The material to be treated is supported by the carrier or apron E and is conducted thereby through the inclosure, which is provided with suitable openings to admit the carrier and the material carried by it. Motion is imparted to one of the drums F for the purpose of moving the carrier by means of a band-pulley G through the medium of suitable gearing or in any other well-known manner.

Arranged within the inclosure A are one or more rollers e for guiding and supporting the apron E. In traversing the inclosure A the apron E passes through the successive compartments B C D.

N N N are the air-moving fans, one of which is placed in each of the compartments B, C, and D. These fans are preferably arranged horizontally in a floor or horizontal partition O immediately below the upper fold of the apron E. The fans N N N may be driven by belt-pulleys N' or in any other well-known manner.

R and Q are heating-coils arranged within the compartment B first traversed by the material under treatment to heat the air-currents, which are circulated therein by the fan N. S is a similar heating-coil arranged in the second compartment C to heat the air therein.

J is an endless guide-apron within the drying-compartments B and C and located immediately above the carrier E.

K K are the rollers or drums which support and guide the aprons J. This guide-apron bears down upon the material under treatment while it is subjected to the upward currents from the fan N, so as to prevent the material being blown from the carrier or apron E by the force of the air-current.

L is a second guide-apron similar to the apron J, running over suitable rollers M M and arranged in the third compartment D.

H is a guide-board at the feeding end of the carrying-apron and outside of the inclosure. One of these guide-boards is placed on each

side of the carrying-apron, and together they form a receptacle or hopper, into which the material to be treated is thrown in the process of feeding the apron or carrier E. 5 I is a guide-roller arranged adjacent to the point at which the carrying-apron enters the drying-inclosure for the purpose of pressing and guiding the material as it passes into the inclosure. This roller also serves to press 10 down and condense the material at the point of entrance to prevent any disarrangement in it which might be caused by the air-currents drawn into the inclosure through the openings provided for the entrance of the 15 material. The roller, being made solid, also serves to block up and close the inlet against the passage of air. This roller is journaled in vertically-sliding bearings *i*, so that it will automatically adjust itself to any variation 20 in the thickness of the material which passes under it.

V is a roller similar to the roller I, arranged adjacent to the outlet-opening of the inclosure A, for guiding and pressing upon the material as it is fed out from the drying-inclosure 25 by the apron E.

T are agitating devices for opening up or agitating the material under treatment at intervals as it passes through the drying-inclosure 30 A. These agitating devices may be variously constructed. I prefer the construction shown in the drawings, consisting of rotating beater-arms arranged above the apron or carrier E. These beaters T stir up the material as it passes under them, so as to loosen 35 and open up the material and present different portions of it to contact with the drying-currents. Arranged adjacent to and above the beaters T are guides *t*, preferably curved, 40 as shown, to guide the material thrown up by the beaters T down upon the carrier E.

W is an air-inlet at the rear end of the inclosure A, and P is an air-outlet arranged at the opposite end opening from the first compartment B. 45

U U U are guide-rollers for guiding the endless apron or carrier E in its passage upon the outside of the inclosure A.

The operation of the apparatus is as follows: The material to be treated is fed from 50 the receptacle or hopper H upon the endless carrier E and is conducted through the drying-inclosure A, passing successively through the compartments B C D therein. It will be observed that these compartments are provided with varying quantity of heating-coils, the compartments B being provided with coils R and Q, which possess large heating 55 capacity, while the compartments C, having only the coil S, will be heated in less degree, and the compartment D, being unprovided with heating devices, will be comparatively cold. The external cold air is drawn into the compartment D by the operation of the fan N 60 and is circulated through that compartment in the manner indicated by the arrows, passing through the material upon the endless carrier 65

E continuously downward in one part and continuously upward in another part of the compartment. A portion of this air is drawn 7c by the second fan N through the opening *b* into the compartment C, and is there circulated in a similar manner to the circulation of the compartment D. The air in this compartment becomes heated by the heating-coils 75 S. A portion of this air is drawn off into the compartment B through the openings *b* by the fan N in said compartment, where it becomes highly heated by contact with the heating-coils R and Q, and after circulation through 8c the compartment in the manner indicated by the arrows it is allowed to escape through the openings P. It will be seen that the air-currents travel through the inclosure A in a direction opposite to that in which the material 85 is carried upon the carrier E and that these air-currents are circulated in each of the series of compartments through the material, the same air being recirculated many times around in each compartment, thus forming a recirculating current of air, the current in one compartment being recirculated entirely independent of any current which is being recirculated in any other compartment. By reason of the variation in the heating appliances in the 95 successive compartments it will be seen that the material is subjected in its passage through the inclosure A to different degrees of heat, the greatest heat being found in the first compartment, into which the material is introduced in its most wet condition, the material when in a comparatively dry condition in the last compartment being treated only by cold-air currents. This is a very important feature in the drying of certain articles which 100 cannot be subjected to a high degree of heat while in a partially-dry condition without injury. Thus in this apparatus as the moisture from the material is evaporated the material is subjected to less heating-currents, the apparatus combining in itself both a hot and a cold air drying machine. It will be observed, also, that the humidity of the air-currents increase with their heat, those in the last compartment being substantially dry. 11

The agitation or opening up of the material while under treatment by means of the beaters T is a very important feature in the drying of many materials, which without agitation would become more or less caked or felted 12 by the action of the air-currents. The stirring up or agitation serves to present different surfaces of the material to contact with the circulating air-current and imparts to the dry materials a light and fleecy nature. 12

While I have shown three compartments B C D in the drawings, with no heating-coils in the last compartment D, my invention is not necessarily limited to that particular number or arrangement, as it is apparent that any 13 convenient number of compartments may be employed and heating-coils may be used in them all.

It is apparent that the quantity of air which

is circulated through the inclosure A depends upon the size of the inlet and outlet openings W and P. Consequently by increasing or diminishing the size of these openings the amount of air circulated through the apparatus and the humidity of the air may be adjusted.

While I prefer the details of construction which are here shown, I do not limit myself to them, as it is apparent that they may be modified without departing from my invention.

Having now described my invention, what I desire to secure by Letters Patent is—

15 1. The combination, in a drying-machine, of external walls or partitions forming a drying-inclosure, one or more interior vertical partitions dividing the said inclosure into two or more drying-compartments, an air-moving fan in each of said compartments to circulate the air therein, a carrier to carry the material to be dried by a continuous motion successively through each of the said drying-compartments, a rotating agitator or opener placed above the carrier for agitating the material thereon and provided with a guide for guiding the agitated material back upon the carrier, inlet and outlet openings from the drying-inclosure to the atmosphere to admit 25 dry cool air at that end of the inclosure where the material is delivered out of the machine by the carrier and to allow the expulsion of the air from the opposite end of the inclosure, and openings through each of said interior vertical partitions to allow the passage of the air from one drying-compartment to another, all arranged to operate as set forth in the specification.

2. The combination, in a drying-machine, 30 of exterior walls or partitions forming a drying-inclosure, an air-moving fan in said inclosure to circulate the air therein, a carrier

to carry the material to be dried by a continuous motion through said inclosure, and a rotating agitator or opener placed above the carrier for agitating the material thereon and provided with a guide for guiding the agitated material back upon the carrier, as shown and described.

3. The combination, in a drying-machine, 35 of external walls or partitions forming a drying-inclosure, one or more interior vertical partitions dividing the said inclosure into two or more drying-compartments, heating devices in one or more of said compartments, an endless carrier to carry the material to be dried by a continuous motion successively through each of said drying-compartments, an air-moving fan in each of said compartments to circulate the air therein and arranged to revolve in a horizontal plane located between the upper and lower folds of the endless carrier, a rotating agitator or opener placed above the carrier for agitating the material thereon and provided with a guide for guiding the agitated material back upon the carrier, inlet and outlet openings from the drying-inclosure to the atmosphere to admit the dry cool air at that end of the inclosure where the material is delivered out of the machine 40 by the carrier and to allow the expulsion of the air from the opposite end of the inclosure, and openings through each of said interior vertical partitions to allow the passage of the air from one drying-compartment to another, all arranged to operate as shown and described in the specification.

In testimony of which invention I have hereunto set my hand.

JOSIAH K. PROCTOR.
